UNITED STATES PATENT OFFICE.

JEROME CORY, OF NEWCASTLE, INDIANA.

FURNACE.

1,124,110.

Specification of Letters Patent.

Patented Jan. 5, 1915.

Application filed April 25, 1914. Serial No. 834,424.

To all whom it may concern:

Be it known that I, JEROME CORY, a citizen of the United States, residing at Newcastle, in the county of Henry and State 5 of Indiana, have invented new and useful Improvements in Furnaces, of which the following is a specification.

The invention relates to furnaces, and more particularly to the class of heating 10 furnaces for use in buildings.

The primary object of the invention is the provision of a furnace wherein the construction thereof permits of a direct upper draft or an indirect down draft from the 15 combustion chamber to the draft flue or chimney of the furnace, thus enabling a slow steady fire with an increase in the heating quality thereof.

Another object of the invention is the 20 provision of a furnace wherein the formation of clinkers is obviated, as well as rendering the furnace smokeless after the fire has been started therein.

A further object of the invention is the 25 provision of a furnace of this character wherein the fire pots or boxes are arranged at opposite sides of the combustion flues or chambers so that water circulating in the furnace will be thoroughly heated before 30 entering the supply system arranged within the building so that maximum heat may be attained with a minimum consumption of fuel.

A still further object of the invention is 35 the provision of a furnace of this character which is extremely simple in construction, reliable and efficient in operation, and inexpensive in manufacture and installation.

With these and other objects in view, the 40 invention consists in the construction, combination and arrangement of parts as will be hereinafter fully described, illustrated in the accompanying drawings, and pointed out in the claims hereunto appended.

45 In the drawings:—Figure 1, is a front elevation of a furnace constructed in accordance with the invention. Fig. 2 is a sectional view on the line 2—2 of Fig. 1. Fig. 3 is a vertical transverse sectional view through 50 the medial portion of the furnace. Fig. 4 is a sectional view on the line 4—4 of Fig. 1. Fig. 5 is a fragmentary sectional view similar to Fig. 2, showing the slide damper and swinging damper in open position for 55 the down draft in the furnace.

Similar reference characters indicate cor-

responding parts throughout the several views in the drawings.

Referring to the drawings in detail, the furnace comprises a casing A formed from 60 sections 10, 11 and 12 between which are arranged packings 13 to form a tight joint therebetween. Passed through the head and through swells 14 at opposite sides of the casing A are tie rods 15 which firmly unite 65 the sections of the casing A together. Arranged within the sections 11 and 12 of the 70 casing A are upper and lower heating chambers or flues 16 and 17 respectively, which at their front ends communicate with 75 a heating chamber 18 formed in the section 10 and common to both of said chambers, while the rear ends of the chambers 16 and 17 communicate with a smoke pipe 19 through openings 20 and 21 for the respective chambers.

Arranged about the chambers 16, 17 and 18 and interiorly of the casing A about the head and sides thereof is a water circulating space or jacket 22. Arranged at opposite sides of the chambers 16, 17 and 18 and within the casing A are combustion spaces 23 or chambers 23 which communicate at their lower ends with a fire pit 24 provided in the lowermost portion of the casing A, while 85 arranged in the lower ends of the spaces or chambers 23 are fuel beds or grates 25, which are of the rocking type, and each has its pivot shaft journaled in bearings 26, the shaft at its front end being extended 90 through an opening in the front wall of the casing A for the attachment of a shaker handle 27 therewith so that the fuel can be dumped into the fire pit when desired.

Hinged to the front wall of the casing 95 A are ash doors 28, clinker doors 29, fire doors 30, and a clean out door 31, respectively, which are usual in the construction of furnaces, each ash door being provided with the usual draft door 32.

100 Adapted to be tapped to a nipple 33 on the section 11 and at the head of the casing A is the water main of the hot water supply system directed through the house, and of the ordinary well-known construction, while tapped in one side of the section 11 is the connection 34 of the return pipe system so that the water after becoming cool in the house and also the water of condensation can be let into the water circulating space 22 after passing through the 105 supply system through the house, as is 110

usual. The upper and lower chambers 16 and 17 communicate with the chamber 18 at the front of the furnace, while the sides of the upper chamber 16 in the section 12 5 are formed with openings 35, which establishes communication between the combustion chambers 23 and the upper chamber 16 in the furnace casing A at the rear thereof.

10 It will be apparent that the water jacket 22 in the sections 11 and 12 is extended transversely of the furnace to form a horizontal partition which divides the chamber 16 at the upper part of the furnace from 15 the chamber 17 at the lower part of the same, and this partition terminates at its front end without the section 10, thus the chamber 18 communicates with both the chambers 16 and 17, while the chambers 23 20 communicate with the chamber 16 through the openings 35 in the section 12 of the furnace.

19 Swingly supported upon a pivot 36 is a damper 37, which when lowered rests upon 25 a seat 38 and is adapted to close the lower portion of the smoke pipe from communication with the upper portion thereof, it being understood of course that the smoke pipe is connected with the chimney or draft flue for the furnace, while slidably fitted 30 in the chamber 16 in the section 12 is a damper 39 which is adapted to close the opening 20, thereby shutting off communication between the said chamber 16 and the 35 upper portion of the smoke pipe 19, the damper 39 being fitted with an operating rod or handle 40 which extends forwardly through the front wall of the furnace so that the said damper can be manually 40 opened or closed, while connected to the pivots 36 of the damper 37 is an arm 41 to which is connected a rod 42, the same being pivotally connected to a bell crank lever 43 supported exteriorly of the casing 45 A of the furnace and to which is pivotally connected a hand operating rod 44 supported by the casing A of the furnace and projected beyond the front wall thereof. It will be obvious that both dampers 37 and 50 39 can be opened and closed when desired.

55 Tapped in the front section 10 of the casing A at the head of the furnace is a water intake pipe 45, while near the lower end of this section and tapped in one side thereof is a drain outlet pipe 46, so that water can be let into the circulating space 22 and drained therefrom, as will be apparent.

Now, to set the furnace for a direct upward draft therein the dampers 37 and 39 60 are manipulated to open the same so that the draft will be created through the openings 20 and 21 from the chambers 16 and 17 above the fire supported by the grates 25 within the furnace. Now, should a downward indirect draft be necessary, the damper 65

39 is shifted to a position for closing the opening 20, thereby shutting off communication between the upper chamber 16 and the upper portion of the smoke pipe 19 so that the products of combustion will be deflected 70 from the rear of the chamber 16 toward the front of the furnace downwardly through the chamber 18 and rearwardly through the chamber 17 to the smoke pipe 19, and thence outwardly through the chimney leading 75 therefrom.

From the foregoing it is thought that the construction and manner of operation of the device will be clearly understood, and therefore a more extended explanation has been 80 omitted.

What is claimed is:—

1. In a furnace, a casing having intermediate and outer chambers, a water jacket surrounding the said chambers and extended about the top and sides of the casing and having a horizontal portion between the walls of the intermediate chamber for dividing it into upper and lower portions, the said horizontal portion of the water 85 jacket terminating spaced from the front of the casing for establishing communication between the upper and lower portions of the said intermediate chamber at the front of the casing, the side walls dividing the intermediate and outer chambers being provided with openings near the rear of the casing for establishing communication between the outer chambers and the uppermost portion of the intermediate chamber, fire grates arranged within the lower portions of the outer chambers, a draft flue having communication with the upper and lower portions of the intermediate chamber, a slide damper movable to opposite sides of the 90 openings in the side walls dividing the intermediate and outer chambers and also controlling the communication between the upper portion of the intermediate chamber and the draft flue, and means for shutting off communication between the lower portion of the intermediate chamber and the draft flue. 95

2. In a furnace, a casing having intermediate and outer chambers, a water jacket 115 surrounding the said chambers and extended about the top and sides of the casing and having a horizontal portion between the walls of the intermediate chamber for dividing it into upper and lower portions, the said horizontal portion of the water jacket terminating spaced from the front of the casing for establishing communication between the upper and lower portions of the said intermediate chamber at the front of the 120 casing, the side walls dividing the intermediate and outer chambers being provided with openings near the rear of the casing for establishing communication between the outer chambers and the upper 125 portion of the intermediate chamber. 130

most portion of the intermediate chamber, fire grates arranged within the lower portions of the outer chambers, a draft flue having communication with the upper and lower portions of the intermediate chamber, a slide damper movable to opposite sides of the openings in the side walls dividing the intermediate and outer chambers and also controlling the communication between the upper portion of the intermediate chamber and the draft flue, means for shutting off communication between the lower portion of the intermediate chamber and the draft flue, and means working through the front of the casing and connected with the slide damper for operating the same.

3. In a furnace, a casing having an intermediate and outer chambers, a water jacket surrounding the said chambers and extended about the top and sides of the casing and having a horizontal portion between the walls of the intermediate chamber for dividing it into upper and lower portions, the said horizontal portion of the water jacket terminating spaced from the front of the casing for establishing communication between the upper and lower portions of the said intermediate chamber at the front of the casing, the side walls dividing the intermediate and outer chambers being pro-

vided with openings near the rear of the casing for establishing communication between the outer chambers and the uppermost portion of the intermediate chamber, fire grates arranged within the lower portions of the outer chambers, a draft flue having communication with the upper and lower portions of the intermediate chamber, a slide damper movable to opposite sides of the openings in the side walls dividing the intermediate and outer chambers and also controlling the communication between the upper portion of the intermediate chamber and the draft flue, means for shutting off communication between the lower portion of the intermediate chamber and the draft flue, means working through the front of the casing and connected with the slide damper for operating the same, and means operable from the front of the casing for controlling the means for closing communication between the lower portion of the intermediate chamber and the flue.

In testimony whereof I affix my signature in presence of two witnesses.

JEROME CORY.
